Henry G. Reed's Design for a Tea Pot. Des 981

Patented Jan'y 12. 1858.

Des. 981

Henry G. Reed, of Taunton Mass. the
Assignor to —
Himself and Charles E. Burton, of same place.

Letters Patent No. 981. dated Jan. 12th 1858.

The schedule referred to in these Letters Patent & making part of the same.

Dec. 981

To all persons to whom these presents shall come:

Be it known that I, Henry G. Reed of Taunton, in the County of Bristol and State of Massachusetts, have invented or produced a new ornamental design for a Tea-Service, or Tea-pot; and do hereby declare that the same is fully described and represented in the accompanying drawing, which denotes the said design as applied to a Tea Service or Tea-pot, and the particulars of the design being delineated with all the minuteness necessary for a skilful pattern maker or silver plate worker to comprehend and work the same into a tangible form.

The figure exhibits a fluted vase A, supported by an ornamental foot B, and furnished with a fluted cover C, surmounted by a group of strawberries and leaves. To the opposite sides of the vase a spout or discharge tube D, and a handle E, are respectively applied, each being ornamented so as to add to the design of the body or vase, the particular ornamentation of each member being as shown in the drawing.

I claim the design as represented and described.

In testimony whereof I have hereunto set my sig-
nature this 17th, day of Dec. 1857. J. M. B.

Witnesses:—
Wm A. F. Sproat.
A. Bassett.
